GEORGE J. PUTH
INVENTOR.

BY
Richard D. Owen
ATTORNEY.

UNITED STATES PATENT OFFICE.

GEORGE J. PUTH, OF APPLETON, WISCONSIN.

SNOWPLOW.

Application filed April 22, 1921. Serial No. 463,487.

To all whom it may concern:

Be it known that I, GEORGE J. PUTH, a citizen of the United States, residing at Appleton, in the county of Outagamie and State of Wisconsin, have invented certain new and useful Improvements in Snowplows, of which the following is a specification.

This invention relates to snowplows and 10 has for its principal object to provide a plow of this nature which is provided with means whereby the snow may be efficiently pushed to one side.

Another object of the invention is to provide 15 a snowplow with heating means so as to prevent the snow from sticking thereto.

A still further object of the invention is to generally improve upon snowplows of 20 this character by providing a mechanism which will be of extremely simple, durable and inexpensive construction, one which is efficient and reliable in operation and well adapted to the purpose for which it is designed.

25 With these and numerous other objects in view, the invention resides in certain novel features of construction and the combination and arrangement of parts as will be hereinafter fully described and claimed.

30 In the drawings:—

Figure 1 is a side elevation of a vehicle showing the snowplow attached thereto,

Figure 2 is a top plan view of a vehicle showing the snowplow attached thereto,

35 Figure 3 is a front elevational view of the snowplow, and

Figure 4 is a side elevational view thereof.

Referring to the drawing in detail it will be seen that 1 designates a motor vehicle of 40 any preferred construction to the forward end of which is attached the snowplow 2. This snowplow 2 includes the body portion 3 and the extensions 4. This extension is disposed at an obtuse angle to the body portion 3 as is shown to advantage in Figure 2. The body 3 and extension 4 are curved throughout their height so as to form scooped-shaped members. The body portion 3 is provided with a rear wall 4 so as 45 to form the compartment 5. The exhaust pipe 6 is in communication with the compartment 5 and will lead from the internal combustion engine on the motor vehicle 1. This exhaust pipe 6 may lead from any engine 50 which it is desired to place upon the vehicle 1 so that the burnt gases or ex-

hausted steam may be delivered to the compartment 5 so as to heat the inner wall 7 of the body 3 thereby preventing the snow from sticking or freezing thereto. The body 50 portion 3 of the plow 2 is attached to the motor vehicle by means of brace rods 8 while the extension is attached to the vehicle 1 by means of the brace rod 9. Any other suitable means may be used for properly 55 mounting the plow. The rods 8 are connected to each other adjacent the axle 10 and are suitably journaled thereon and provided with an extension 11 indicated in dotted lines in Figure 2. The rod 9 60 is also journaled to the axle 10 and is provided with the extensions 12 and 12' shown in Figure 1. A pair of worms 13 are suitably journaled in brackets 14 so as 65 to extend vertically and the threads of these worms 13 are engaged by the extensions 11 and 12. Each worm 13 is provided with a beveled gear 15 in mesh with beveled gears 16 carried on shafts 17. Beveled gears 18 are suitably mounted on the inner ends of 70 these shafts 17 and are in mesh with a beveled gear 19 keyed to the shaft 20 which is operable by the wheel 21. By proper rotation of wheel 21 it will be seen that the rods or extensions 11 and 12 may be turned on 75 the axle 10 thereby raising or lowering the plow 2. The extension 12' is adapted to engage the vehicle 1 when the plow is in a raised position and the extension 12 engaged with the bottommost thread of the worm 13. 80 An arm 23 is suitably attached to the arm 9 and extends through the extension 4 and is provided at its end with the journal 24 for receiving the shaft 25 which extends parallel with the extension 4. A suitable fan or 85 propeller 26 is fixed to the end of the shaft 25 adjacent the body 3 and suitable means are provided for the rotation of this propeller 26 so as to draw the snow from the body 3 into the extension 4 and force it to 90 the side of the road. In this particular illustration of my invention I have disclosed a beveled gear 27 suitably keyed to the shaft 25 intermediate its ends which beveled gear 95 is in mesh with beveled gear 28 fixed on shaft 29 at the other end of which is provided a gear 30 in mesh with gear 31 which is rotated by any suitable means such as through the gearing 32 driven by the motor 33. 100

110 From the foregoing description, taken in connection with the accompanying draw-

ings, the construction and operation of the snowplow will be readily understood without a more extended explanation. As numerous changes in form, proportion, and in 5 the minor details of construction may be resorted to without departing from the spirit of this invention I do not wish to be limited to the construction herein shown and described other than as claimed.

10 Having thus described my invention what I claim as new is:—

In combination, a vehicle, a plow, means for pivotally attaching the plow to the vehicle, a bar attached at one end to the plow

and fulcrumed intermediate its ends to the 15 vehicle, a worm mounted on the vehicle so as to be engaged by the other end of said bar, means for turning the worm so as to raise and lower the plow, and an extension formed on the bar for engagement with the 20 vehicle so as to limit the upward movement of the plow.

In testimony whereof I affix my signature in presence of two witnesses.

GEORGE J. PUTH.
